Francis R Pearson

United States Patent Office.

FRANCIS R. PEARSON, OF GERMANTOWN, PENNSYLVANIA.

Letters Patent No. 63,085, dated March 19, 1867.

IMPROVEMENT IN SPINNING-JACKS.

The Schedule referred to in these Letters Patent and making part of the same.

TO ALL WHOM IT MAY CONCERN:

Be it known that I, FRANCIS R. PEARSON, of Germantown, city and county of Philadelphia, and State of Pennsylvania, have invented certain new and useful Improvements in Spinning-Jacks for spinning woollen yarn; and I do hereby declare that the following is a full, clear, and exact description of the construction and operation of the same, reference being had to the annexed drawings, making a part of this specification, in which—

Figure 1 is a top view.

Figure 2 is a side view.

Figure 3 is a front view.

Other drawings are details.

Similar letters in the drawings refer to like parts.

My improvement consists in a mechanical arrangement of a friction motion to a spinning-jack, to assist the operator or spinner in the working of the same.

To enable others to make and operate my improvement, I will proceed to describe its construction and operation, reference being had to the annexed drawings, making a part of this specification.

b, in figs. 2 and 3, is the main driving-belt, which communicates motion to the jack by the pulley *3*. The belt shifter *f* is constructed and supported in the usual manner, with this exception, that the shifter-bar is not positively connected to the levers which operate it by the movements of the carriage and twist-gearing; that is to say, that this lever, on all jacks heretofore built, connecting the twist gear with the shifter-bar, is slotted at that part where it connects with the shifter-bar. In this slot is a pin or stud, fastened to the shifter-bar. This slot I dispense with, and by the action of the spring *5* the pin is drawn against the lever connecting with the twist-gearing. The twist-gearing and the lever connecting it with the shifter-bar are not shown in the drawings, as these parts are all old and well known to spinners and operators of spinning-jacks. The object is to allow the friction motion to operate without moving the twist-gearing. To this shifter I fasten the spiral spring *5*. The pin *i*, fig. 3, presses against the right-angled lever *u*, when the belt is on the loose pulley. The lever *u* is fastened to the frame by the stand *w*, fig. 3. In one of the arms of this lever is a slot. (See details.) The end of this rests on the nut on the connection-rod *v*. The rod *v* is connected to the T-shaped lever *g*, which is pivoted on a stud in the stand *l*, which stand is fastened to the floor. To the lower end of the lever *g* is connected the rod *r*. This rod is supported by the stands *1*, *2*, and *h*, fastened to the floor and between the centre slip and the race-belt of the jack. The rod *r* extends out to the end of the slip. On the outer end of the rod *r* is cut a thread, on which is fitted the lug *o* and nut *t*. At the extreme bottom of the lever *g* is fastened the spiral spring *6*. This spring is made of greater power than the spring *5*, connected to the shifter-bar *f*, fig. 1. The other end of the spring is fastened to the floor. In the top of the stand *h* is the catch *e*, fitted to a stud pin so that it will work freely. *C* represents the carriage, *n* the faller. To this faller is connected the wire *p*, having a loop at the lower end. This wire is steadied by the staple *x* at the bottom of the carriage, fig. 2. On the back of the carriage is a stand. In this stand is fitted a stud, *s*, set at the same height as the top of the lever *g*.

The operation is as follows: In putting the carriage up, the stud *s*, in the rear of the carriage, presses the lever *g*, and forces back the rod *r*. When, by this back movement, the catch *e* locks on the lug *o*, and the carriage is drawn out the full stretch, the operator backs off; and in putting down the faller *n* the loop on the wire *p* raises the catch *e*, the spring *6* draws the lever *g* back till the nut *t* on the end of the rod *r* strikes the stand *h*, which is set so as to allow the spring to shift the belt on the tight pulley *3* sufficiently far to assist the operator in putting up the carriage, it being regulated by the nut *t*. As soon as the carriage is put up, and before the jack is put in gear, the friction is taken off, so that, when the operator stops to piece up ends that may be broken, the friction will be entirely off.

Having thus described my invention, I would state that I am aware there are other devices invented and patented, which accomplish the same object, differing only in their construction and operation. The advantages in my improvement are, first, my arrangement, which does not positively connect the belt-shifter bar to the twist-gear, and controlling the movements of the said bar in one direction by connecting it to a spiral

spring. The same result may be effected by an elliptic spring, but a spiral spring is preferable. Second, by cutting the regulating screw on the rod *r*, and operating the catch from the front of the carriage, which arrangement enables me to construct a very simple yet efficient and adjustable friction motion, which I claim to be a decided improvement on all other friction motions in use as known to me.

Claims

I claim—

1. Actuating the belt-shifter bar *f* in one direction by means of the twist-gearing, and in the other direction by the spiral spring, the whole combined and arranged substantially as described and for the purpose set forth.
2. I claim the combination and arrangement of the catch *e*, loop *p*, and faller *n*, constructed as described, and operated from the front of the carriage, substantially as described and for the purpose set forth.
3. I claim the combination of the rod *r*, lug *o*, catch *e*, stand *h*, and nut *t*, when constructed as described for the purpose set forth.

FRANCIS R. PEARSON.
